UNITED STATES PATENT OFFICE.

HERBERT S. WALBRIDGE, OF NORTH BENNINGTON, VERMONT.

DESIGN FOR A HOOD FOR STEREOSCOPES.

SPECIFICATION forming part of Design No. 26,943, dated April 20, 1897.

Application filed February 16, 1897. Serial No. 623,742. Term of patent 14 years.

To all whom it may concern:

Be it known that I, HERBERT S. WALBRIDGE, of North Bennington, in the county of Bennington and State of Vermont, have 5 invented and produced a new and original Design for a Hood for Stereoscopes, of which the following is a full, clear, and exact description.

Reference is to be had to the accompanying 10 drawings, forming a part of this specification, in which similar characters of reference indicate corresponding parts in both the figures.

Figure 1 is a rear view of a stereoscope-hood embodying my new design. Fig. 2 is an inverted view looking in the direction of the 15 arrow shown in connection with Fig. 1.

The design in its entirety shows a hood *a* of elliptical form in general, the hood having at its front the lens-frame *b*. The hood at 20 the sides rises, as at *a'*, to a point above the center of the top *a²*, the lines of the edge being in curves. At the bottom of the hood a bridge-piece *c* appears, which completes the hood and is of inverted-V shape in general, 25 its sides ranging alongside each other at the

upper end between the lenses *b' b'*, as at *c' c'*, presenting a division-wall therebetween, but terminating short of the top of the hood, as seen clearly in the rear view, Fig. 1. The sides of the bridge, further, range in curved 30 lines laterally and overlap the major portion of the hood, as at *c² c²*, and the sides are of increased depth from their inner adjacent ends *c' c'* to their outer ends *c²*, as seen in Fig. 2. 35

The leading feature of my design consists in a hood of elliptical shape in general, and which at its under side is continued from both sides inward in approximately V shape, the terminals thus continued ranging at their 40 inner ends alongside each other between the lenses of the hood, and of decreasing width toward such inner ends.

I claim—

The design for a hood for stereoscopes, 45 herein shown and described.

HERBERT S. WALBRIDGE.
